CLAIM

The ornamental design for a fuel container, as shown and described.

DESCRIPTION

FIG. 1 is a side elevational view of a fuel container showing my new design, the opposite side being a mirror image thereof;

FIG. 2 is a front elevational view;

FIG. 3 is a bottom plan view;

FIG. 4 is a rear elevational view; and

FIG. 5 is a top plan view thereof.

FIG. 5

FIG. 4
